Atty.

UNITED STATES PATENT OFFICE

ERNST DIETRICH, OF ALtenburg, GERMANY

TURRET FOR MULTIPLE PUNCHING MACHINES

Application filed May 28, 1929, Serial No. 366,592, and in Germany June 1, 1928.

My invention relates to a turret for multiple punching machines, and more particularly to the means for securing the plungers to the turret. Difficulties are often encountered when articles of somewhat irregular configuration are punched as projecting parts of the articles interfere with certain punches so that the turret cannot rotate freely. It is an object of my invention to overcome this difficulty and to this end I provide in combination with a set of plungers each of which has a guiding bush inserted in a recess of the turret, clips for holding the bushes in their recesses which clips are detachably secured to the turret, and stops on the turret for locating the bushes by entering a recess in each bush.

The clips are readily detached for releasing any bush which interferes with the free rotation of the turret, and the bush comes off its stop as readily.

It is another object of my invention to provide means for securing the plungers in their bushes. To this end I provide a spring catch in each stop which is adapted to enter a depression or recess in the plunger.

In the drawing affixed to this specification and forming part thereof a turret head embodying my invention is illustrated diagrammatically by way of example.

In the drawing:

Fig. 1 is an elevation showing part of the upper disc of a turret head, with three plunger and stripper units therein,

Fig. 2 is a section taken through the axis of one of the units, and part of the turret disc,

Fig. 3 is a plan view showing the three units illustrated in Fig. 1, in plan view,

Fig. 4 is an elevation showing part of the lower disc of the head, with one of the dies,

Fig. 5 is a plan view of the die,

Fig. 6 is a section on the line 6—6 in Fig. 4, and

Fig. 7 is an elevation of the complete machine.

Figs. 8 to 10 illustrate on a smaller scale various positions of the means for reciprocating the plungers, more particularly,

Fig. 8 is an elevation showing one of the

plungers about to enter into operative connection with the reciprocating means,

Figs. 9 and 10 are end elevations viewed from the right in Fig. 8 and showing the reciprocating means elevated and lowered, respectively, and

Fig. 11 is a section on the line 11—11 in Fig. 8.

Referring first to Fig. 7, 5, 5a are the parallel upper and lower parts of a machine frame, 4 is a pin secured in the frame, 3 is a boss fitted to rotate on the pin 4, 1 is the upper disc supporting the plunger-and-stripper units, 7, 8, and 2 is the lower disc supporting the dies 19. The parts 1, 2 and 3 make up the turret of the machine, and 14 is the usual manually operated lever at the punching station.

Referring now to Fig. 1, 2 and 3, 6 are recesses in the perimeter of the upper disc 1 of the turret, 7 are bushes inserted in the recesses, 12 are clips adapted to engage the bushes 7 on the outside, and 13 are screws for holding down the clips on the bushes 7. 8 is a plunger which is fitted to slide in each bush 7, and is engaged by the reciprocating means illustrated in Figs. 8 to 11, 18 is a punch at the lower end of the plunger, 15 is a circular groove at the upper end of each plunger, 26 is a rod which is fitted to slide in the frame 5, 5a under the control of the usual lever 14 and a cam, not shown, and 24 is a jaw at the lower end of the rod 26 which is substantially U-shaped as shown in Figs. 9 and 10. The jaw is arranged tangentially with respect to the circular path along which the plungers rotate bodily about the axis of the pin 4, and is provided with inwardly projecting flanges at its lower end, a clearance 25 being left between the flanges. It will appear that as the plungers arrive in succession at the punching station below the lever 14, their heads are engaged by the flanges entering into the grooves 15. When a plunger has entered the jaw as shown in Fig. 9, the rod 26 is lowered by means of the lever 14 as shown in Fig. 10 so that the lower end of the plunger descends upon the corresponding die 19.

Each bush is recessed at the top for the re-

ception of a stop plate 10 which is secured on the upper disc 1 by means of a screw 11. By these means the bush is located in its recess axially and circumferentially. 16 is a catch which is fitted to slide in each plate against the action of a spring 17 and adapted to enter a recess in the plunger 8 so that the plungers and bushes are held in a given position with respect to the upper disc 1, and 10 their upper ends, with the grooves 15, are at the same level.

Referring now to Figs. 4, 5 and 6, means are provided for aligning the dies 19 in the lower disc 2 exactly with respect to the corresponding plungers. The dies are provided with reduced extensions 20 at their lower ends which fit with some clearance in holes provided for them in the lower disc 2. Each extension has a circular groove adapted to 20 be entered by oppositely tapered pins 21 and 22, as best seen in Fig. 6. 23 are threads of opposite hands at the ends of the pins which engage female threads in the disc 2. The threaded ends 23 are slotted for the attack 25 of a screw driver so that they will be displaced axially by being rotated, and in this manner smaller or larger radii of the pins are brought to bear on the die, causing a corresponding transverse displacement of the 30 die.

It will be understood from this description that when difficulties of the kind referred to are encountered, for instance, if a plunger is obstructed by a projecting part of the article 35 so that the plunger which has been operated at the punching station, could not move on, the obstructed plunger is readily removed by unscrewing its screw 13. Obviously, the upper ends of the plungers must be at the 40 same level in order to be properly engaged by the jaw 24, as described, and therefore it is not practicable to raise an obstructed plunger so that it will jump the obstruction, but the only possibility is to remove it temporar- 45 ily.

The facility of removing the plungers obviously has the additional advantage that they are readily exchanged for plungers of larger or smaller size, as required. Any irregularity which may be brought about by exchanging the plungers is readily removed by adjusting the dies 19, as described with reference to Figs. 4-6.

I wish it to be understood that I do not desire to be limited to the exact details of construction shown and described for obvious modifications will occur to a person skilled in the art.

In the claims affixed to this specification no 60 selection of any particular modification of the invention is intended to the exclusion of other modifications thereof and the right to subsequently make claim to any modification not covered by these claims is expressly re- 65 served.

I claim:

1. In a turret for multiple punching machines having a set of plungers, the combination with recesses in said turret of guiding bushes for said plungers each adapted to be 70 inserted in one of said recesses, a clip adapted to hold said bush in said recess, means for detachably securing said clip to said turret so as to hold said bush, each bush being recessed at its upper end, and a stop on said turret which is adapted to enter said recess.

2. In a turret for multiple punching machines having a set of plungers, the combination with recesses in said turret of guiding bushes for said plungers each adapted 80 to be inserted in one of said recesses, a clip adapted to hold said bush in said recess, means for detachably securing said clip to said turret so as to hold said bush, each bush being recessed at its upper end, a stop on said 85 turret which is adapted to enter said recess, and a spring catch in said stop adapted to enter a recess in said plunger.

In testimony whereof I affix my signature.
